No. 19,010.

Patented Apr. 9, 1889.

UNITED STATES PATENT OFFICE.

JAMES L. FOLSOM, OF BROOKLYN, NEW YORK, ASSIGNOR TO THE HARTFORD CARPET COMPANY, OF HARTFORD, CONNECTICUT.

DESIGN FOR A CARPET.

SPECIFICATION forming part of Design No. 19,010, dated April 9, 1889.

Application filed March 7, 1889. Serial No. 302,342. Term of patent 3½ years.

To all whom it may concern:

Be it known that I, JAMES L. FOLSOM, a citizen of the United States, residing in Brooklyn, county of Kings, and State of New York, have 5 invented a new and original Design for Carpets, of which the following is a specification, reference being had to the accompanying photograph, which forms a part of the same.

The invention relates to a design to be 10 worked into or upon surfaces, such as carpets or similar fabrics; and it consists in the novel configuration and grouping of figures herein specifically shown and claimed.

The accompanying photograph is a face 15 view of a carpet showing my new design.

My design consists of the body A and the border B. The body A is made up of irregular figures with small ornamentation of various kinds therein. The border B has an inner 20 band composed of irregular figures with small

ornamentation, and an outer band containing groups of fan-shaped figures, and a central figure for each repeat composed of interlacing irregular lines. Ornamental figures having a waving outline form the separating 25 margin of these two bands.

What I claim as new, and desire to secure by Letters Patent, is—

1. The design for carpets, consisting of the body A, substantially as shown. 30
2. The design for carpets, consisting of the border B, substantially as shown.
3. The design for carpets, consisting of the body A and the border B, substantially as shown.

JAS. L. FOLSOM.
